UNITED STATES PATENT OFFICE.

JOHN BILAN, OF FLINT, MICHIGAN.

FAN STRUCTURE FOR AIR-COOLED MOTORS.

Application filed May 24, 1923. Serial No. 641,193.

To all whom it may concern:

Be it known that I, JOHN BILAN, a citizen of Ukraine, residing at Flint, in the county of Genesee and State of Michigan, have invented certain new and useful Improvements in Fan Structures for Air-Cooled Motors, of which the following is a specification.

This invention relates to certain new and useful improvements in fan structures for air cooled motors wherein a current of air is forced through an air chamber formed in the motor casing for the purpose of cooling the motor by air instead of the usual water circulating system.

The primary object of the invention is to provide a fan structure for air cooled motors wherein a casing having a fan revolvably mounted therein, has a conduit connection with an air chamber associated with a motor to create a circulation of air through the motor for the purpose of cooling the same.

With the above and other objects in view as the nature of the invention is better understood, the same consists of the novel form, combination and arrangement of parts hereinafter more fully described, shown in the accompanying drawing and claimed.

In the accompanying drawing, wherein like reference characters designate corresponding parts throughout the several views,

Figure 1 is a longitudinal sectional view of a fan structure for air cooled motors constructed in accordance with the present invention showing the conduit connection between the fan structure and the motor,

Figure 2 is a rear elevational view of the supporting arm for the forward end of the fan structure,

Figure 3 is a side elevational view of the supporting arm shown in Fig. 2,

Figure 4 is a cross sectional view taken on line IV—IV of Fig. 1 showing the closed inner end of the casing for the fan and the lug carried thereby for attaching the inner end of the fan structure casing to the motor,

Figure 5 is a side elevational view of the shaft for supporting the rotatable fan,

Figure 6 is a front end elevational view of the fan structure,

Figure 7 is a rear end elevational view of the fan structure,

Figure 8 is a perspective view of the fan structure showing the relatively short and long fan blades, 55

Figures 9 and 10 show side elevational views of the large and small fan blades, and

Figure 11 is a side elevational view of the 60 anchoring bolt for supporting the outer end of the fan structure upon the motor.

Referring more in detail to the accompanying drawing, the fan structure embodies a casing having a cylindrical wall 1 and an inset bottom wall 2 surrounded by a depressed channel 3 inwardly of the side wall 1 as clearly shown in Figs. 1 and 4, the forward open end of the casing having an inwardly directed angular shoulder 4 with spider bars 5 extending across the open end of the casing as shown in Fig. 1. The channel portion 3 of the casing is broken and separated by an intervening portion 2^a of the bottom wall 2 while one end of the channel portion 3 has a conduit 6 formed integral with the casing and extending to an air chamber in the motor 7 illustrated by dotted lines in Fig. 1.

The support for the closed end of the 80 casing includes diametrically opposite apertured lugs 8 carried by the side wall 1 adjacent the channel 3 through which fastening members, such as screw bolts, pass to be secured in the motor 7.

A frame structure encloses the casing and traverses the open forward end thereof, a forwardly positioned bracket comprising abutting plates 9 and 10 with the plate 10 offset as at 10^a having mounting rods 11 85 threaded at opposite ends as at 12 passing through registering openings 13 in opposite ends of the bracket plates 9 and 10 for the reception of lock nuts, while the opposite ends of the bars 12 are secured in the motor 7. 95

The shaft 14 is journaled at one of its ends in the opening 15 in the bottom wall 2 of the casing with the other end thereof rotatably extending through openings 16 in the bracket plates 9 and 10, a pulley 17 being 100 keyed to the shaft 14 intermediate the bracket plates 9 and 10 between the ends thereof as shown in Figs. 1 and 3.

The fan includes a conical drum 18 that is keyed to the shaft 14 within the casing, the conical drum 18 carrying relatively small and large fan blades 19 and 20 respectively with the forward edges of the larger blades

20 having angular cutaway corner edges 20^a to accommodate the angular shoulder 4 upon the forward end of the casing wall 1.

From the above detail description of the 5 device, it is believed that the construction and operation thereof will at once be apparent, it being noted that the rear end of the casing is supported by the lateral lugs 8 upon the motor 7 while the forward end 10 thereof is supported by the spider bars 5 through which the rotatable shaft 14 extends, a belt passing over the pulley 17 to rotate the shaft 14 and fan wheel as shown in Figs. 1 and 8 carried thereby. Air is drawn in 15 through the open front end of the casing and driven toward the rear closed end thereof, filling the chamber 3 and traveling therein to the outlet conduit 6 for delivery to the air chamber in the motor 7 for circulating 20 air through the latter to cool the motor, the angular shoulder 4 upon the casing cooperating with the fan structure to hold the latter in proper position within the casing and upon the shaft 14. The outer end of the 25 shaft 14 with the bracket plates 9 and 10 are supported by the bars 11 to present a rigid structure supporting the fan mechanism.

While there is herein shown and described 30 the preferred embodiment of the present invention, it is nevertheless to be understood that minor changes may be made therein without departing from the spirit and scope of the invention as claimed.

35 What is claimed as new is:—

1. In a fan structure for air cooled motors a casing secured to the motor, a bracket traversing the forward end of the casing, supporting bars for the bracket secured to 40 the motor, a shaft journaled in the bracket and casing, a fan secured to the shaft within the casing, a discharge conduit extending from the casing, said bracket comprising a pair of bars with one of the bars offset

intermediate the ends and a belt pulley 45 secured to the shaft intermediate the bracket bars.

2. In a fan structure for air cooled motors, a casing secured to the motor, a bracket traversing the forward end of the casing, 50 supporting bars for the bracket secured to the motor, a shaft journaled in the bracket and casing, a fan secured to the shaft within the casing, a discharge conduit extending from the casing, said bracket comprising 55 a pair of bars with one of the bars offset intermediate the ends, a belt pulley secured to the shaft intermediate the bracket bars, said casing being open at its forward end and a circular channel formed in the closed 60 inner end of the casing separated by a portion of the inner end wall with the conduit connected to one end of the channel.

3. In a fan structure for air cooled motors, a casing secured to the motor, a bracket 65 traversing the forward end of the casing, supporting bars for the bracket secured to the motor, a shaft journaled in the bracket and casing, a fan secured to the shaft within the casing, a discharge conduit extending 70 from the casing, said bracket comprising a pair of bars with one of the bars offset intermediate the ends, a belt pulley secured to the shaft intermediate the bracket bars, said casing being open at its forward end, a circular channel formed in the closed inner end 75 of the casing separated by a portion of the inner end wall with the conduit connected to one end of the channel, said fan including a conical drum secured to the shaft, fan blades carried by the drum, the forward outer corner edges of alternate blades having angle notches therein and the outer peripheral edge of the casing having an inwardly directed angular shoulder extending 80 into the blade notches.

In testimony whereof I affix my signature.
JOHN BILAN.
